CLAIM

The ornamental design for a neuromuscular junction cell culture layer as shown and described.

DESCRIPTION

Figure 2.1 is a top perspective view of a neuromuscular junction cell culture layer showing our new design;

Figure 2.2 is a top view thereof;

Figure 2.3 is a bottom view thereof; and

Figure 2.4 is a side view thereof.

The broken lines in the drawings depict portions of the neuromuscular junction cell culture layer that form no part of the claimed design.
